Rollander & Stratton

ATTORNEYS.

UNITED STATES PATENT OFFICE

HENRY HOWARD KOB, OF FORT COLLINS, COLORADO

WRENCH

Application filed May 26, 1930. Serial No. 455,626.

My invention relates to wrenches. The principal object is to provide a strong, compact and simple construction for a wrench whose jaws are always parallel, whether apart or together.

Another object of the invention is to provide handles or levers for such jaws that provide efficient means for operating the jaws. Still other objects of the invention will appear in the course of the following description.

While the invention resides in the novel construction and arrangement of parts, it is to be understood that changes may be made in same without departing from the scope and spirit of the invention.

In the drawings like reference characters designate similar parts in the several views.

Figure 1 shows an elevation of an embodiment of my invention.

Figure 2 is a partly broken elevation, similar to that shown in Figure 1, with a movable jaw, comprised in the invention, disposed in a different position.

Figure 3 is a section taken on the line 3—3 of Figure 1.

Figure 4 is a section taken on the line 4—4 of Figure 1.

Referring more in detail to the drawings, the reference numeral 5 designates a relatively fixed handle or lever. A relatively movable handle or lever 6 is pivoted to the fixed handle by means of a bolt 7, which acts as a fulcrum. A nut 8, bearing against a shoulder 9 of the bolt, holds the bolt in position.

The bolt extends through an opening 10 in the movable handle and through slots 12 in the fixed handle. The body 30 of the fixed handle has side plates 13 that are spaced apart to receive the movable handle therebetween. The movable handle operates between stops 14 and 15 on the body of the fixed handle. The body member 30 carries a relatively fixed jaw 16.

The side plates 13 have inward ribs 17. A movable jaw 18, slidably mounted on the body 30, is grooved, as shown at 19, to be engaged by the ribs 17. The movable jaw has a boss 20 and a stem 21. The stem 21 is re-

cessed, as shown at 22, and slides in an opening 23 of the fixed jaw.

The movable handle 6 has shoulders 24 and 25 which abut against the ribs 17 to limit the opening and closing movements of said handle. The handle 6 also has a curved recess 26 to receive the boss 20. Movement of the handle 6 is communicated to the movable jaw 18 through the medium of the boss and recess. Fingers or abutments 27 and 28, respectively 60 projecting beyond the shoulders 24 and 25, engage the boss and movable jaw at opposite sides. The finger 28 is disposed in the recess 22 of the movable jaw stem and in some positions is between the ribs 17. The recess 22 not only receives the tip of the finger 28, but also a considerable part of said finger, when the handles are in an open position, as shown in broken lines in Figure 2.

In the use of the invention, it will be clear 70 that my wrench may be used in either of two adjusted positions, depending upon whether the bolt 7 is in the upper part or lower part of the slots 12. In Figure 1, the closed position of the wrench is shown in full lines and the open position is shown in dotted lines. In said view, the bolt is in the upper part of the slots. In Figure 2, the full lines represent a closed position of the jaws, and the dotted lines represent the open position of the 75 jaws; in which positions the bolt is in the lower part of the slots.

As the handles 5 and 6 are separated, the jaw 18 is moved away from the jaw 16, through the intermediary of the boss and engaging fingers. The stem 21 traveling in the opening 23, holds the movable jaw in the desired positions relative to the fixed jaw, and strengthens the wrench.

The ribs 17 not only provide sliding surfaces for the groove 19 of the movable jaw, but also provide abutments for the shoulders 24 and 25 to limit opening and closing movements of the handle 6.

What I claim and desire to secure by Letters Patent is:

1. A wrench comprising pivotally connected, crossed handles, a relatively stationary jaw on one handle and a relatively movable jaw on the same handle, said handle also 100

having an internal rib and the movable jaw having a groove disposed to be engaged by the rib, and the other handle being operatively connected with the movable jaw and disposed to abut against the rib to limit movement of the handle.

2. A wrench comprising pivotally connected, crossed handles, a relatively stationary jaw on one handle and a relatively movable jaw on the same handle, said handle also having an internal rib and the movable jaw having a groove disposed to be engaged by the rib, and the other handle having fingers disposed at opposite sides of the movable jaw to move same, the fingers having shoulders to abut against the rib on the first-mentioned handle, to limit opening and closing movements of said other handle.

3. A wrench consisting of a longitudinally and transversely slotted handle, a relatively stationary jaw on the handle, a relatively movable jaw, the handle and the latter jaw having engaging rib-and-groove means slidably connecting the movable jaw to the handle, a second handle in the longitudinal slot of the first-mentioned handle, a bolt mounted in the transverse slots of the first-mentioned handle pivotally connecting the handles, the second handle having fingers disposed at opposite sides of the movable jaw for communicating movement thereto, movable in the longitudinal slot of the first handle, and having a shoulder disposed to abut against the rib to limit movement of the handle.

4. A wrench comprising pivotally connected crossed handles, a relatively stationary jaw on one handle and a relatively movable jaw on the same handle, the last-mentioned handle and the movable jaw having engaging rib-and-groove means slidably connecting the movable jaw to the latter handle, the other handle having abutments disposed to limit movements of the movable jaw in opposite directions and to communicate to the movable jaw movements of said other handle.

5. In testimony whereof I hereunto affix my signature.

HENRY HOWARD KOB.
